UNITED STATES PATENT OFFICE.

CARL HARTMANN, OF SAN FRANCISCO, CALIFORNIA.

GAS BURNER.

Application filed July 15, 1924. Serial No. 726,137.

To all whom it may concern:

Be it known that I, CARL HARTMANN, a citizen of the United States, residing in the city and county of San Francisco and State of California, have invented a new and useful Improvement in a Gas Burner, of which the following is a specification.

My invention relates to improvements in a gas burner for heating apparatus and particularly to an improved burner adapted to burn gas directly without a previous admixture with air.

The primary object of my invention is to provide an improved gas burner.

Another object is to provide an improved burner adapted to give a very high degree of heat.

A further object is to provide a burner arranged to burn gas without a previous admixture with air to obtain a higher degree of efficiency from the fuel consumed and to prevent flare back from the burner to an air mixing chamber such as heretofore commonly used.

Another object is to provide an improved burner provided with a reflector element adapted to form an air passage to admit air around and over the burner and to reflect heat from below the burner upwardly to an element to be heated.

A further object is to provide an improved device of the character described provided with improved lighting means adapted to prevent the turning on of the fuel supply when the lighting means is closed.

I accomplish these and other objects by means of the device disclosed in the drawings forming a part of the present specification wherein like characters of reference are used to designate similar parts throughout said specification and drawings and in which,

Fig. 1 is a broken side elevation, partly in section, of my improved burner as applied for use in connection with a water heater.

Fig. 2 is a plan view of the burner.

Fig. 3 is a broken side elevation of the valve fittings.

Referring to the drawings, the numeral 1 is used to designate in general a burner consisting of a plurality of tubular burner arms 2 each provided with a plurality of restricted apertures 3. The arms 2 are connected to a common central supply pipe 4

connected through a suitable control valve 6 to a source of gas supply, not shown. The arms 2 are closed at their outer ends, and are made arcuate in shape so as to obtain a maximum length of tube and a maximum number of burner apertures 3 confined within a relatively small area.

A ring 7 is mounted around the burner 1 by means of supporting arms 8 carried by a collar 9 mounted upon the supply pipe 4 in connection with the valve 6, said ring 7 being provided with an annular shoulder 11 arranged to receive and form a support for an element to be heated by the burner. In Fig. 1 of the drawings I have illustrated the burner in connection with a water heater of conventional type wherein a water circulating coil 12 is enclosed above the burner 1 by means of a housing 13 resting upon the shoulder 11 of the ring 7.

A concave reflector 14 is mounted upon the supply pipe 4 immediately below the burner, the edge of said reflector being spaced slightly below the lower edge of the ring 7 to form an air passage 16 therebetween whereby air may be admitted around the burner 1.

A pilot burner 17 is mounted adjacent the burner 1, said pilot burner opening immediately above the burner arms 2 and being connected to the supply pipe 4 through a tubular member 18 and a valve 19 tapped into the side of the housing of the valve 6 in communication with gas supply thereto. The valve 19 is provided with an actuating lever 21 whereby the valve may be operated to control the supply of gas to the pilot burner 17, said lever being arranged immediately below a lever 22 provided upon the valve 6 whereby said valve 6 may be operated to control the supply of gas to the main burner 1. The lever 21 is arranged to cross under the lever 22 at substantially right angles when the valve 19 is in closed position so that the lever 22 cannot be operated to open the valve 6 until the valve 19 has been opened. When the valve 19 is opened to permit the lighting of the pilot burner the lever 21 is moved from under the lever 22 thereby permitting free operation of the main valve 6. This arrangement insures that the pilot valve will be open and the pilot burner presumably lighted before the main burner can be turned on, in this manner insuring the immediate lighting of the burner when the valve 6 is opened and pre-

venting the escape of gas and also preventing explosions due to the tardy igniting of the gas should the valve 6 be opened when the pilot burner is shut off.

5 It will be noted that the burner is connected to the source of gas supply through closed connections so that gas is supplied to the burner arms 2 directly without being first mixed with air as has heretofore been 10 the common practice. The gas, under the normal supply pressure is thus allowed to issue through the apertures 3 in its pure state. The apertures 3 are made very small so that the gas will issue in a very small stream at 15 a relatively high velocity and burn as a long thin flame at very high temperature. As the gas burns above the burner 1, air is drawn in through the air passage 16 to combine with the gas and support the combustion so that 20 the gas will be completely burned. The restricted area of the aperture 3 is an important feature of the structure as by this means a long blue flame is produced from each of the apertures 3, whereas a larger 25 opening, such as used in the ordinary gas burner operating in conjunction with an air mixing chamber, would result in a short red flame of much lower temperature and which would only partially consume the gas issuing 30 from the burner. By providing a plurality of apertures 3 along each of the arcuate arms 2 a large number of very hot flames are produced within a relatively small area immediately under the element 35 to be heated, thereby causing the element to be quickly heated with a minimum consumption of fuel.

Having thus described my invention what I claim as new and desire to secure by Letters Patent is,

40 1. A gas burner comprising a plurality of arms each having a plurality of restricted apertures; a ring mounted around the burner arms and adapted to receive an element to be heated; a reflector mounted below the arms and ring and having its upper 45 edge in slightly spaced relation to the lower

edge of the ring to form an annular air passage around the burner arms; and a valve controlling the passage of gas to the 50 burner arms whereby gas from a source of supply may be caused to issue from the restricted apertures in the arms without prior admixture with air for burning below and around the element to be heated, the combustion of said gas being supported by air admitted around the burner arms only through the passage between the reflector and the ring.

55 2. A gas burner comprising a plurality of 60 arms each having a plurality of restricted apertures; a closed passage for directing gas from a source of supply directly through said apertures; a supporting element mounted around the burner arms to support an element to be heated above the arms; and a concave reflector mounted below the burner arms and spaced below the supporting element to form an air passage to admit air around the burner arms to combine with and support combustion of the gas above the 65 burner arms, said reflector being adapted to reflect heat upwardly from below the burner.

70 3. A gas burner comprising a plurality of 75 arms each having a plurality of restricted apertures; a closed passage for directing gas from a source of supply directly through said apertures without previous admixture with air; a supporting element 80 mounted around the burner arms to support an element to be heated above the arms; a reflector mounted below the burner arms and spaced from the supporting element to form an air passage whereby air is admitted 85 around the burner arms to combine with and support combustion of the gas above the burner arms; and a pilot/burner connected to the source of gas supply and opening immediately above the burner arms for igniting the gas when the supply is turned on.

In witness whereof I hereunto set my signature.

CARL HARTMANN.
